HOUSING FOR AN AUTOMOTIVE TRAFFIC SIGNAL

Jack A. Press, Jr., 3590 Rockerman Road,
Miami, Fla. 33133

Filed July 1, 1968, Ser. No. 12,566

Term of patent 14 years

Int. Cl. D29—99

U.S. Cl. D72—1

FIG. 1

FIG. 2

FIG. 4

FIG. 3

FIG. 1 is a top plan view of a housing for an automotive traffic signal showing my new design.

FIG. 2 is a side elevational view, the obverse side being identical.

FIG. 3 is a bottom plan view.

FIG. 4 is a side elevational view as seen 90 degrees from the side view shown by FIG. 2, the obverse side being identical in design.

FIG. 5 is a cross sectional view taken along the line 5—5 of FIG. 1.

The lettering is shown in broken lines in FIGS. 2 and 4 for illustrative purposes only.

I claim:

The ornamental design for a housing for an automotive traffic signal, substantially as shown and described.
